JOURNAL DRESSER

William Ruby, Fresno, Calif.

Application February 8, 1946, Serial No. 646,413

5 Claims. (Cl. 51—187)

1

This invention relates in general to repair equipment for railroad cars.

The invention is directed in particular to, and it is an object to provide, a wheel-truck journal dresser of a design adapted to be used on the road for the purpose of accomplishing temporary repair of a scored journal whereby the railroad car can be run a sufficient distance to reach a repair depot for attention. In this manner replacement of wheel trucks on the road, which is costly and difficult, can be avoided.

Another object of the invention is to provide a wheel truck journal dresser which is light weight, compact in design, and easy to position on a journal to dress down the same; the device being arranged so that it may be manually or power actuated.

A further object of the invention is to provide a journal dresser which comprises a driven disc adapted to be disposed concentrically at the end of a journal, spring fingers projecting from the periphery of the disc in overhanging relation to the journal, arcuate dresser shoes mounted on said fingers and matchingly engaging the journal.

A further object of the invention is to produce a practical journal dresser, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation, mainly in section, of the device as in use on a railroad wheel truck journal.

Fig. 2 is an end view of the device, with the crank handle detached.

Fig. 3 is an end view of one of the dresser shoes, detached, but having the corresponding supporting finger engaged therewith.

Fig. 4 is an enlarged cross section on line 4—4 of Fig. 2.

Fig. 5 is a back view of one of the dresser shoes, detached, showing the manner of attachment of the emery cloth thereto.

Fig. 6 is a perspective view of a modified form of dresser shoe, detached.

Referring now more particularly to the characters of reference on the drawings, the device comprises a circular supporting disc 1 adapted to be disposed at the outer end of a wheel-truck journal J which is scored, and which must be dressed before the journal box can be re-brassed and the railroad car used. The disc is formed with a central opening 2 to align with the usual

2

tapered centering socket 3 or seat in the journal; the disc having an outwardly projecting non-circular socket 4 symmetrically disposed relative to opening 2.

At circumferentially spaced points the disc 1 is fitted, on the outside, with radially extending finger attachment units, each of which is indicated generally at 5. In the present embodiment there are four of these finger attachment units 10 disposed 90 degrees apart. Each of the finger attachment units 5 comprises a radial, outwardly opening channel 6 fixed on the disc 1 and having a finger attachment base 7 hinged therein, adjacent its outer end, by a pivot pin 8 for radial swinging movement. An adjustment screw 9 is threaded through each base 7 adjacent its inner end and bears against the bottom of the channel 6, whereby said base may be adjusted about the pivot pin 8.

Normally only a pair of opposed ones of the finger attaching units 5 are used, and which is as follows:

A pair of flat spring fingers 10 extend in overhanging relation to the journal J on opposite sides thereof but parallel to the journal axis; said spring fingers extending across the disc 1, and having radially inwardly offset portions 11 therein, whereby the inner ends of said fingers are disposed in adjacent but spaced relation to the surface of said journal.

At their outer ends the pair of flat spring fingers 10 are formed with inturned attachment tongues 12 slotted lengthwise, as at 13, with said slots open to the inner ends of such fingers.

The slotted attachment tongues 12 each extend between a locking plate 14 and the adjacent base 7 of the corresponding finger attachment unit 5, said tongue straddling holding screws 15 which secure the locking plate 14 to the base 7. By tightening the holding screws 15 the adjacent attachment tongue 12 is positively clamped between the locking plate 14 and the base 7.

On opposite sides of the journal and inwardly of the flat spring fingers 10 the device comprises a pair of transversely arcuate dresser shoes 16, which dresser shoes are of a length substantially equal to the length of the journal, and said shoes are each faced on the concave side thereof with a sheet of emery cloth 17. Each dresser shoe 16 is fitted, on the back, with a central, attachment head 18 which is slotted lengthwise of the shoe, as at 19, for the sliding reception, in said slot, of the inner end portion of the corresponding flat spring finger 10.

Tie wires 20 extend through transverse eyes 21 at the ends of each attachment head 18, and said wires diverge and connect, at their ends,

with the sheet of emery cloth 17 whereby to maintain the latter in place.

When the above described device is assembled on a journal J, as shown in Fig. 1, and at which time the flat spring fingers 10 and dresser shoes 16 are disposed on opposite sides of said journal, the adjustment screws 9 of the opposed finger attachment units 5 which are in use are adjusted to position the hinged bases 7 so that said spring fingers 10 are under sufficient tension to relatively forcefully urge said dresser shoes radially inwardly.

The disc is then rotated about journal J by means of a spindle 22 which projects through opening 2 and has a tapered point 23 to fit socket 3 and an axially adjustable head 24 (here shown as a pair of lock nuts) to engage socket 4. The reason for the head 24 being adjustable along the spindle, while being rigid therewith, is so that point 23 will engage the bottom of socket 3 irrespective of the depth of the latter, and which depth is apt to vary. Spindle 22 is here shown as being part of a hand crank 25. Rotation of the disc causes the dresser shoes 16 to smooth the journal sufficiently to remove substantially all bad scoring, sharp cuts, scum, etc. With this device the journal can be dressed down enough to permit re-brassing of the journal and running of the car, with the journal cool, to a depot for complete and permanent repairs. The device is intended only for use in connection with the temporary repair of journals on the road, and which repair can only be made after the bad journal has been exposed by jacking up the adjacent portion of the railroad car. This, however, is a relatively easy task as compared with replacement of an entire wheel truck, which has heretofore been necessary when a journal failed when the car was in transit.

In instances where the journal is particularly badly scored or damaged, such journal is first dressed by a plurality of file-faced dresser shoes 26, one of which is shown in Fig. 6. Each of such shoes is of substantially the same configuration as the dresser shoes 16, but is of lesser arcuate extent, and is formed on the face as a file 27. Each shoe 26 includes a central attachment head 28 slotted, as at 29, for the reception of the spring fingers 10.

When the file shoes 26 are used, it is preferable that four be employed, in which instance there are four spring fingers 10 which engage in the four finger attachment units 5 mounted on the supporting disc 1.

After the journal has been dressed with the file shoes 26 they are removed, and thereafter the dressing operation is finished, with the dresser shoes 16, which include the emery cloth 17, on the working faces thereof.

While the device has here been described as rotated by a hand crank 25, it is obvious that power rotation of such device may be employed if desired, as by means of an electric or compressed-air motor.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the fol-

lowing is claimed as new and useful and upon which Letters Patent are desired:

1. A journal dresser comprising a supporting disc adapted to be disposed in concentric relation at the end of a journal for rotation about the axis thereof, a plurality of dresser shoes each having a working face, said dresser shoes being adapted to engage the journal in circumferentially spaced relation, a spring finger connected at one end to each dresser shoe and extending lengthwise of the journal in overhanging relation to the disc, inturned attachment tongues on the adjacent ends of the fingers, radially extending base members on the outside of the disc adjacent the tongues, said base members being pivoted adjacent their outer ends on the disc for swinging relative thereto in radial planes, means attaching the tongues to corresponding base members, adjustment screws threaded through the base members inwardly of their pivots and bearing against the disc, and means to rotate the latter.
2. A journal dresser as in claim 1 in which the tongue attaching means on each base comprises a locking plate facing the base, and holding screws extending between the locking plate and base, each tongue being slotted and frictionally engaging between the corresponding locking plate and base in straddling relation to the holding screws thereon.
3. A journal dresser comprising a supporting disc, a plurality of dresser shoes, each shoe having a working inner face and an attachment head on its outer face, such head being provided with a substantially rectangular slot therethrough, a plurality of flat spring fingers mounted on the disc and extending in substantial parallelism with the central axis of such disc, each finger projecting through the slot in one of said attachment heads in sliding relation therein.
4. A journal dresser comprising a supporting disc, a dresser shoe, a finger on the shoe, the finger having a longitudinally slotted end extending at substantially right angles thereto, a support on the disc, such end being positioned in the support, and set screws threaded into the support and projecting through the slot in the end whereby the finger may be adjusted and set at different distances radially outward of the central axis of the disc.

5. A journal dresser comprising a supporting disc, a dresser shoe supported from the disc, such shoe having an inner working face and an attachment head on its outer face, the attachment head having a transversely disposed eye at each end, a tie wire disposed in each eye, said wires having divergent ends, and means at each end of each wire for attachment to abrasive material wrapped about the working face of the shoe.
